Philip Simons, INVENTOR.

BY
Geo. P. Kimmel.

ATTORNEY.

UNITED STATES PATENT OFFICE.

PHILIP SIMONS, OF PEWAMO, MICHIGAN.

HARROW OR DRAG TOOTH.

Application filed August 23, 1922. Serial No. 583,877.

To all whom it may concern:

Be it known that I, PHILIP SIMONS, a citizen of the United States, residing at Pewamo, in the county of Ionia and State of Michigan, ⁵ have invented certain new and useful Improvements in a Harrow or Drag Tooth, of which the following is a specification.

This invention relates to improvements in harrows, and has for one of its objects to ¹⁰ improve the action of the spring teeth of harrows or "drags" by providing the free end of each tooth with a lateral earth engaging cutting offset, to materially increase the width of the cut or furrow, and arranging ¹⁵ the teeth and the offsets in staggered relation, so that all portions of the furrow are uniformly acted on and no ridges or other uneven portions produced.

Another object of the invention is to provide ²⁰ a device of this character having means whereby the tooth will yield to abnormal strains and thus prevent breakage of the parts.

Another object of the invention is to provide ²⁵ a device of this character in which means are provided for rigidly connecting the offset to the body of a resilient tooth, to reinforce and stiffen the union between the tooth and the offset.

With these and other objects in view, the invention consists in certain novel features of construction as hereinafter shown and described and then specifically pointed out in the claim, and in the drawings illustrative of the preferred embodiment of the invention:—

Figure 1 is a side elevation of one of the improved harrow teeth attached to a conventional tooth bar, the latter being in trans- ⁴⁰ verse section,

Fig. 2 is a front elevation of one of the improved teeth, detached,

Fig. 3 is a plan view of a portion of a conventional harrow frame with a pair of ⁴⁵ the improved teeth members attached.

Fig. 4 is a detached perspective view of one of the combined reinforcing and cutting blades.

The improved device comprises a resilient ⁵⁰ or spring harrow tooth formed in two sections, an upper section 10 and a lower section 10¹, the two sections being coupled by a single bolt 18. The portion 10 of the tooth structure is formed with means such as a

shortly turned terminal 11 adapted to be attached by a bolt 12 to the tooth bar 13.

At its free end the portion 10¹ is extended laterally as at 14, the extension being preferably inclined downwardly and rearwardly away from the body of the tooth, as shown. ⁶⁰

Attached to the under face of the extension 14 is a reinforcing member 15, the latter extended at one end as at 16 to engage the body 10 at its juncture with the extension 14, to support the extension and stiffen ⁶⁵ and strengthen the union between the parts. The reinforcing member 15—16 is rigidly secured in position by rivets 17 or the like.

The extension 14 is directed at a slight angle both downwardly and rearwardly ⁷⁰ away from the portion 10¹ of the tooth, so that it draws through the earth with a "shearing" action, thereby materially reducing the friction and consequently decreasing the power required to draw the harrow ⁷⁵ through the earth.

The improved teeth are attached to the bars 13 in "staggered" relation, as illustrated in Fig. 3, so that the earth engaging members engage every portion of the earth or "furrow" and uniformly operate thereon, and obviate the formation of ridges or untreated ⁸⁰ "lands."

The bolts 18 will be of sufficient strength to hold the portions 10 and 10¹ against normal strains while in operation, but will yield if the earth engages an abnormal resistance such as a root, stone, or the like and thus avoid breaking any of the parts. ⁸⁵

Any number of the bars 13 may be employed and any number of the improved teeth attached to each bar, as required. ⁹⁰

By this simple construction all of the marked advantages of the spring or resilient harrow or drag tooth are retained and in addition an effectual earth engaging means provided whereby all parts of the "furrow" are uniformly treated and the formation of ridges, or "lands" or untreated portions obviated. ⁹⁵

The spring tooth or harrow or drag on account of its yieldable qualities possesses certain marked advantages in working certain kinds of ground, and which tend to pulverize the soil much better than a solid tooth. ¹⁰⁰

In the present device all of the advantages of the spring tooth are retained and in addition the very marked advantage of the in- ¹⁰⁵

clined rigid offset cutting blades operates slightly beneath the surface of the soil, and by overlapping obviates the formation of ridges or "lands."

- 5 The preferred embodiment of the invention is disclosed in the drawings and set forth in the specification, but it will be understood that modifications within the scope of the claimed invention may be made in
10 the construction without departing from the principle of the invention or sacrificing any of its advantages.

Having thus described the invention, what is claimed as new is:

A resilient harrow tooth having a lateral 15 offset at its outer end, and a cutting blade attached to the offset portion and extending in advance of the forward edge of the same, said cutting blade upturned at one end to bear against and reinforce the tooth member at its juncture with the offset.

In testimony whereof, I affix my signature hereto.

PHILIP SIMONS.
